Primary Examiner — Kevin K Rudzinski*Assistant Examiner* — Amber J Rabie(74) *Attorney, Agent, or Firm* — Jinggao Li(57) **CLAIM**

The ornamental design for a protective case for earphone, as shown and described.

DESCRIPTION

FIG. 1 is a perspective view of a protective case for earphone showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof in a use state; and,

FIG. 9 is an enlarged view of portion 9 shown in FIG. 1.

The broken lines depict portions of the protective case for earphone and form no part of the claimed design.
